J. M. CALKINS

TOOTHBRUSH

Filed Nov. 26, 1926

INVENTOR
J. M. CALKINS
BY *Munn & Lee*
ATTORNEYS

UNITED STATES PATENT OFFICE.

JAMES MURPHY CALKINS, OF DETROIT, MICHIGAN.

TOOTHBRUSH.

Application filed November 26, 1926. Serial No. 150,847.

My invention relates to improvements in tooth brushes, and it consists in the combinations, constructions, and arrangements herein described and claimed.

5 An object of my invention is to provide an improvement over my Patent No. 1,600,975, issued September 28, 1926. The improvement consists in providing a device which is simpler in construction, which is 10 more easily operated, and which may be used more efficiently.

The only manner in which teeth may be thoroughly cleaned is by moving the brush back and forth from the gum to the end of 15 the teeth and positioning the head of the brush in substantial alignment with the row of teeth being cleaned. By positioning the head of the brush in this manner, the bristles may readily extend between the teeth, and 20 by movement of the bristles, all the substance lodged between the teeth may be readily removed therefrom. This cannot be performed by the ordinary type of tooth brush, and it is an object of applicant's invention to 25 provide a device by means of which this may be accomplished.

A further object of my invention is to provide a device of the type described in which the handle may be adjusted to various 30 positions so that the head may be moved so as to clean the teeth properly.

A further object of my invention is to provide a device of the type described in which the handle may be moved to any desired 35 position and firmly held in this position without removing the head of the brush from the mouth.

A further object of my invention is to provide a device of the type described in which a head of special construction is provided for cleaning the outer surfaces of the teeth, and a head of special construction is provided for cleaning the inner surfaces of the teeth.

45 A further object of my invention is to provide a device of the type described in which the handle may be readily removed from one of the brush heads and readily inserted in the other.

50 A further object of my invention is to provide a device of the type described in which the handle is firmly held in the head of the brush during its movement into the various positions.

55 Other objects and advantages will appear in the following specification, and the novel

features of the invention will be particularly pointed out in the appended claims.

My invention is illustrated in the accompanying drawings, forming part of this application, in which

Figure 1 is a plan view of the device, a portion thereof being broken away,

Figure 2 is a section along the line 2—2 of Figure 1,

Figure 3 is an enlarged bottom plan view of one end of the handle.

Figure 4 is a brush head for cleaning the outer surfaces of the teeth, and

Figure 5 is a brush head for cleaning the inner surfaces of the teeth.

In carrying out my invention, I provide two brush heads indicated generally at A and B, both having backs 1 and 2 which are identical in construction. These backs are 75 provided with substantially rectangular-shaped recesses 3 and 3'. The backs are provided with enlarged portions 4 and 4' beneath the recesses 3 and 3' and enlarged portions 5 and 5' above the recesses 3 and 3'. 80 The backs 1 and 2 are provided with pivot pins 6 and 6' which are positioned substantially at the center of the heads within the recesses 3 and 3'.

The outer surfaces of the enlarged portions 4 and 4' and 5 and 5' are substantially areuate-shaped forming their arcs from the centers of the pivot pins 6 and 6'. These surfaces are formed of substantially flat engaging surfaces 7, 7', 8, 8', 9, 9', 10, 10', 90 11 and 11'.

The enlarged portions 4 and 4' are provided with openings 12 and 12'. Resilient strips 13 and 13' are rigidly secured at one end to the lower extremities of the pivot pins 6 and 6', and extend outwardly perpendicular to the rear surfaces of the recesses 3 and 3'. Retaining lugs 14 and 14' are disposed in the openings 12 and 12' and are rigidly secured at their lower ends to the 100 resilient strips 13 and 13'. The retaining lugs 14 and 14' have rounded upper ends 15 and 15' for a purpose hereinafter described.

The head A is provided with two sets 105 of bristles 16, the free ends of which provide a substantially concave surface 17. A recess 16' is provided between the sets of bristles 16. The head B is provided with two sets of bristles 18, the free ends of which 110 form a substantially convex surface 19. A recess 18' is provided between the sets of

bristles 18. The ends 20 and 21 of the backs 1 and 2 are tapered inwardly so that the heads may be readily inserted into the mouth and moved freely therein without injuring the mouth in any way.

A removable handle 22 is provided with an integral tongue 23. The tongue 23 is provided with a relatively large arcuate-shaped surface 24 and a relatively small arcuate-shaped engaging surface 25. An arcuate-shaped groove 26 which is also arcuate-shaped in cross section is disposed substantially adjacent the arcuate-shaped surface 24. Semi-circular recesses 27 and 28 are disposed in the tongue 23 at the outer extremities of the groove 26. Openings 29, 30 and 31 are disposed through the tongue 23 within the groove 26. The handle 22 is provided with an enlarged portion 32 which has an arcuate-shaped recess 33 and shoulders 34 and 35.

From the foregoing description of the various parts of the device, the operation thereof may be readily understood. In cleaning the teeth, either the head A or the head B may be used first. Let us assume that the operator wishes to use the head B first. In this event, the tongue 23 of the handle 22 is inserted into the recess 3' after the resilient strip 13', together with the lug 14', has been moved downwardly. By releasing the strip 13' and the lug 14' after the handle has been adjusted to the desired position, the lug 14' will project into one of the openings or the recesses. Let us assume that the operator wishes to have the handle 22 in the farthest position to the left, viewing Figure 1. The lug 14' will be received in the recess 27. With the handle in this position, the operator may thoroughly clean the teeth upon the inside and to the rear of the mouth. In cleaning the teeth nearer the front and upon the inside, the handle 22 is swung into the next farthest position, or that position next to the center position on the left, viewing Figure 1. The handle 22 may be readily swung into this position without removing the brush from the mouth, but by merely gripping lightly upon the brush head by the mouth and swinging the handle 22 so that the lug 14' with the aid of the rounded end 15' will be swung out of the recess 27, ride along the groove 26, and be received in the opening 29. In like manner, the handle 22 may be swung into the other three positions; that is, the center position indicated in full lines, and the two positions to the right indicated in dotted lines.

The groove 26 is of sufficient width to permit the handle 22 to move outwardly a slight distance when the handle is moved from one position to another. This is to permit the shoulders 34 and 35 of the handle to move by the adjacent corners and into engagement with the adjacent engaging surfaces. The lug 14', as it is being forced into one of the

openings 29, 30, and 31, or the recesses 27 and 28, draws the tongue 23 and the handle 22 inwardly so that the walls of the arcuate-shaped recess 25 will bear against the pin 6, and the shoulders 34 and 35 of the handle 70 bear against the desired engaging surfaces.

When the operator has thoroughly cleaned the teeth upon the inside, the resilient strip 13' is forced outwardly a sufficient distance to free the lug 14' from the tongue 23 and 75 permit the tongue 23 to be removed from the recess 3'. The tongue 23 of the handle 22 may now be inserted into the recess 3 by moving outwardly the resilient strip 13, together with the lug 14. When the strip 13 is 80 released, the lug 14 locks the tongue 23, together with the handle, in any desired position.

It is obvious that the handle 22 may be 85 swung into any of the five positions indicated in Figure 1 by merely gripping the head A in the mouth and swinging the handle 22 to any of the desired positions. During this movement, the tongue 23 swings about the pin 6 as a pivot. The arcuate-shaped groove 26 prevents the removing of the tongue 23 from the recess 3 during the swinging of the handle into the various positions by the cooperation of the lug 14. The groove 26 also guides the lug 14 into any 90 one of the openings 29, 30 and 31, or the recesses 27 and 28. The pin 6 also supports 95 the resilient strip 13.

The enlarged portions 4 and 4' reinforce 100 the backs 1 and 2. These enlarged portions are positioned upon the sides of the backs adjacent the bristles and in no way interfere with the operation of the device. The resilient strips 13 and 13' are also positioned upon the enlarged portions 4 and 4' and 105 within the recesses 16' and 18'. The recesses 16' and 18' enable the operator to readily actuate the resilient strips 13 and 13' and the lugs 14 and 14'. The recesses 16' and 18' also aid in the cleaning of the teeth as 110 they straddle a tooth and enable the sets of bristles on each side thereof to more thoroughly clean those portions on each side of the straddled tooth.

The enlarged portions of the backs 1 and 2 are substantially arcuate-shaped and the shoulders 34 and 35 of the handle 22 firmly engage any of the desired engaging surfaces 115 of these enlarged portions so that the device may be readily used and swung into any of the desired positions without injuring the mouth of the user in any way.

I claim:

1. A tooth brush comprising a back having a recess therein, an enlarged portion integral 125 with said back and having a plurality of flat engaging surfaces at the entrance to said recess, a handle having an integral shouldered extension, an adjoining flange integral with said handle said extension arranged in 130

said recess, said handle adapted to be moved with respect to said back for bringing said shoulder into engagement with any of said engaging surfaces, and means for locking 5 said extension in said recess, whereby said shoulder is firmly held adjacent one of said engaging surfaces.

2. A tooth brush comprising a back having a recess therein, a pin disposed through said 10 back and said recess, a handle, a tongue integral with said handle and having an arcuate-shaped recess in the outer end thereof for receiving said pin, said handle and said tongue adapted to be swung about said pin, 15 and means for engaging with said tongue for removably securing said tongue and said handle in any desired position with respect to said back.

3. A tooth brush comprising a back having

a recess and an opening therein, a pin disposed through said back and said recess, a resilient strip rigidly secured at one end to said pin, a lug rigidly mounted upon said strip and extending through said opening, the free end of said lug extending into said recess, a handle, and a tongue integral with said handle and having an arcuate-shaped recess in the end thereof, said tongue having an arcuate-shaped groove and openings 30 equally spaced within said groove, the recess in said back being adapted to receive said tongue when said strip and said lug are moved outwardly, the arcuate-shaped recess in said tongue being adapted to receive said pin, and said lug being receivable in any one 35 of the openings in said tongue.

JAMES MURPHY CALKINS.
